UNITED STATES PATENT OFFICE.

HENRY K. WHITE, OF MERIDEN, CONNECTICUT, ASSIGNOR TO WILCOX & WHITE ORGAN COMPANY, OF SAME PLACE.

REED-ORGAN ACTION.

SPECIFICATION forming part of Letters Patent No. 286,516, dated October 9, 1883.
Application filed May 7, 1883. (No model.)

To all whom it may concern:

Be it known that I, HENRY K. WHITE, of Meriden, in the county of New Haven and State of Connecticut, have invented new Improvements in Reed-Organ Actions; I do hereby declare the following, when taken in connection with accompanying drawing and the letters of reference marked thereon, to be a full, clear, and exact description of the same, and which 10 said drawing constitutes part of this specification, and represents a side view of a key and the connecting-lever.

This invention relates to an improvement in reed-organs, with special reference to that class 15 in which the valves are arranged on a vertical board at the rear of the key-board, and is an improvement on the invention for which Letters Patent were granted to me March 27, 1883, No. 274,686, but is applicable to other 20 organs in which the action is produced upon a lever standing substantially vertical to the plane of the key-board. In my previous patent, as in other organs of this character, the movement of the key is imparted to the levers 25 of the valves by means of an arm extending from the key either up or down. In such arrangement the leverage of the key is necessarily short, and requires considerable pressure to depress the keys.

30 The object of my invention is to reduce the force required to be applied to the keys in order to open the valves; and it consists in a system of toggle-like levers beneath the key, whereby the power of the key over the action 35 is greatly increased, and as more fully herein-after described.

A represents one key of the organ, and will 40 fully illustrate the invention, as the devices are simply duplicated for all the keys in which this advantage is desirable.

B is the lever through which the keys or the levers of the action are operated, and to which the power of the key is directly applied. This lever takes its bearing at a at a 45 point below the keys, near the front.

D E are two parts of the toggle, one end of the part E resting in the bearing C, the other end hinged to the forward end of the part D, as at b. The rear or inner end of the part D 50 takes its bearing in the lever E, as at d. From the key a pin, e, extends downward and bears

upon the back of one of the parts D E of the toggle, preferably upon the part E, and near the joint. This pin is fast in the key, and should be made adjustable—as, for instance, by making it screw-threaded it turns into or from the key, as occasion may require. The two parts D E are inclined upward toward their joint, so that they are above a direct line between the two bearing-points C and d. Therefore when 60 the key is depressed the parts D E are correspondingly depressed and approach a direct line between the two points C d, as seen in broken lines. This depression forces the part D rearward, because the part E is held from 65 forward movement, and this rear movement, produced by the strengthening movement of the toggle, turns the lever B rearward and opens the valves. Then, as the pressure is removed from the key, the springs, as before 70 described, return the toggles and force the key upward. As the extent of downward movement in extending the toggle is very much greater than the rear movement produced thereby, it follows that the force produced by 75 the power applied is very much greater than that power so applied and in accordance with the well-known law of toggle-joints.

I claim—

1. The combination of the key A, the parts D E of the toggle, arranged beneath the key, the rear end of one part of the toggle having its bearing on a corresponding valve-lever, and the other part of the toggle being supported in a rigid bearing at the front, whereby the depression of the key is communicated to the valve-levers through said toggle, substantially as described.

2. The combination of the key A, the parts D E of the toggle, arranged beneath the key, the rear end of one part of the toggle having its bearing on a corresponding valve-lever, and the other part of the toggle being supported in a rigid bearing at the front, whereby the depression of the key is communicated to the valve-levers through said toggle, and the adjustable pin e between the key and toggle, substantially as described.

HENRY K. WHITE.
